UNITED STATES PATENT OFFICE

2,677,584

GARMENT BAG HANGER FRAME

Michael Schulman, Philadelphia, Pa.

Application December 6, 1950, Serial No. 199,402

12 Claims. (Cl. 312—5)

1

This invention relates to garment bags and, more particularly, relates to hanger frames for suspending flexible garment bags.

Full-size voluminous flexible garment bags with two or more hooks passing through the upper end of the bag material and intended to be hooked over a horizontal rod from which the bag may be suspended, have been previously available. These bags are usually supported by a hanger frame and open along one side to receive a plurality of garments draped on ordinary coat hangers which may be suspended from an internal transverse garment rack forming part of the frame.

With garment bags of this type, it is with the greatest of inconvenience that garments are removed from or replaced in the bag. Delicate feminine garments, for which these bags are largely used, are particularly susceptible to damage during struggles to install on a centrally disposed garment rack such garments while groping at arm's length in the dark recesses of a swaying bag, more especially when other garments are already in place.

It is one of the principal objects of my invention to provide a garment bag and hanger frame therefor in which this objectionable feature is obviated.

Another object of my invention is to provide a garment bag and hanger frame arranged for stable suspension, in which a transverse garment rack is slidably movable between a median and a forward position in the bag.

A further object of this invention is to produce a garment bag with a closable forward opening and a hanger frame having a garment rack slidable between a median and a forward position in the bag.

Still another object of the invention is to produce an inexpensive efficient durable garment bag hanger frame which is removable from the bag and which provides optimum accessibility to the garments stored therein.

With these and other objects in view which will become apparent from the ensuing description and claims, the following sets forth the details of construction and combination of parts of a specific embodiment of my invention, which I illustrate as an example, and which will best be understood when read in conjunction with the accompanying drawing, in which:

Fig. 1 is a fragmentary perspective view of a garment bag and hanger frame constructed in accordance with my invention, showing the bag closure flap in open position and the garment rack in full forward position.

2

Fig. 2 is a perspective view of the hanger frame of my invention with the garment rack in an intermediate position.

Fig. 3 is a side elevational view of the device of Fig. 2 with stabilizing rod in place, showing the folded position of the supporting hooks in broken lines.

Figs. 4 and 5 are enlarged fragmentary front and side elevational views respectively, partly in section, of the ball slide bearing of the device of Fig. 2.

Fig. 6 is a fragmentary side elevational view, partly in section, of the garment bag of my invention showing alternate methods of eliminating forward angular tilting.

Fig. 7 is a perspective view of a modification of the hanger frame of my invention.

Figs. 8 and 9 are enlarged fragmentary views, partly in section, of roller bearing modifications of the side sliders of the device of Fig. 7.

Fig. 10 is a perspective view of another modification of the hanger frame of my invention.

Figs. 11 and 12 are enlarged fragmentary front and side elevational views respectively, partly in section, of the ball slide bearing of the device of Fig. 10.

Referring now to the drawing, I have shown in Fig. 1 a rectangular garment bag 15 made of suitable fabric or flexible plastic material. Within the upper end of the bag 15 is a supporting hanger frame 16 having two hooks 17 disposed in spaced relation along the transverse median from front to rear of the bag for supporting the bag on a closet rod 19. The hooks 17 pass through reinforced holes 18 in the top of the bag 15 and a stabilizing rod 20 passes upwardly through a similar hole 21 at the middle of the rearward edge of the bag.

The bag 15 is provided with a generally rectangular forward opening 22 the full width of the bag front and extending vertically from just below the bag top to a suitable substantial distance downwardly thereof. The opening 22 is closable with an appropriately dimensioned closure flap 23, shown in open position in Fig. 1, flexibly or hingedly permanently attached to one side of the opening 22 and normally closed by a peripheral conventional slide fastener 24.

The frame 16 is fashioned largely of wire and comprises two track members 25 of relatively heavy and stiff wire, disposed in a horizontal plane and paralleling each other for the full longitudinal depth from front to rear of the bag 15. The forward ends of the two track members 25 are each provided with a short vertical upward extension 26, the ends of which are welded to

the front portion of a rectangular bag support element 21 of lighter gage wire conforming to the contour of the upper end of the bag 15. The rear ends of the two track members 25 are provided with extensions 28 which are bent upwardly for a distance relatively shorter than the length of the forward extensions 26, then are bent toward each other to meet at a central point where they are integrally united (welded together or formed from a single wire) and welded to the rear of a hollow cylindrical sleeve 38 having its axis vertically disposed.

The frame 16 is bilaterally symmetrical, with the track members 25 spaced from the sides of the bag. Slightly to the rear of the median line of the bag depth, there is welded to each track member 25 a brace member 31 directed first vertically upwardly, then bent forwardly and upwardly toward the median, and finally bent horizontally outward and continuing until terminated at conjunction with the adjacent side portion of the bag support element 27, and being welded thereto. Clamped around the inward horizontal part of each of the members 31 for pivotal connection therewith is a sleeve 32 which provides a swivel mounting for the lower end of the hook 17 so that it is free to turn on its shank as an axis.

A transverse rack 33, of wire provided with a series of depressions or seats for carrying coat or garment hangers, depends from the track members 25 and is arranged for sliding translation relative thereto between the forward ends 26 and the brace members 31. Adjacent the ends of the rack 33 and suitably spaced thereon for engagement with the respective track members 25, are two slide bearings 34, each comprising a sheet metal shell 35 and a ball 36, illustrated in Figs. 4 and 5. The shell 35 is of generally inverted U shape with the ends brought together into contact for a substantial distance. The juxtaposed ends of the shell 35 are drilled transversely to receive the rack 33 and are welded thereto. The track member 25 passes through the opening in the shell 35 and is a loose fit therein. The ball 36 is approximately of the same diameter as the cylindrical track member 25 and is mounted over it in the shell opening, being retained therein by the fingers 37 struck down from the slotted ends of the horizontal top portion of the shell 35. To assure the rack 33 being at all times perpendicular to the track members 25, each bearing 34 is provided with a guide rod 38, welded thereto above the rack 33, and extending rearwardly approximately half the bag depth and terminating in a transverse eye 40 encircling the track member 25 in the region between the brace member 31 and the extension 28.

Associated with each track member 25, a tie member 41 of light gage wire is welded to the forward extension 26 at a point above the level of the top of the bearing 34, extends rearwardly and upwardly to the horizontal portion of the brace member 31 and is welded to the inward end thereof, then continues rearwardly and downwardly to the rearward extension 28 and is welded to the vertical portion thereof at approximately the same level as at the forward end.

The bore of the sleeve 30 is a sliding fit on the stabilizing rod 20 which passes therethrough and is limited in downward travel by a locking sleeve 42 which engages the rod 20 with a sliding fit and is adjustably lockable thereto by a thumbscrew 43 transversely threaded into the sleeve 42.

The operation of this device is as follows: The bag 15, mounted on the frame 16, is hung in a closet provided with a rod 19 and the usual overlying shelf 45, with the hooks 17 engaging the rod 19, and the locking sleeve 42 adjusted on the stabilizing rod 20 so that the rod just contacts the lower surface of the shelf 45 when the bag is level or slanting slightly toward the rear. With the flap 23 open and the rack 33 in its forward-most position as shown in Figs. 1 and 3, hangers carrying dresses or other garments are hung in the depressions of the rack, as illustrated by the hanger 44.

The rack 33 is then pushed rearwardly to its limiting position at the median, and the flap 23 is closed and secured with the fastener 24. To remove the garments, the flap is opened and the rack pulled forward to the front of the bag as illustrated in Fig. 1. In this position, with the garments and coat hangers readily accessible, the bag is stable because the plurality of hooks 17 prevent transverse angular tilting of the frame due to unequalized loading, and the stabilizing rod 20 prevents downward tilting of the front of the bag. Downward bending forces on the front and rear ends of the track members 25 are resisted by the truss action of this assembly, tensing the tie members 41, which though of light gage are quite strong in tension, and compressing the track members 25 which are of suitable columnar strength. The bag 15, which is light in weight, receives adequate support from the support element 21, even though this element is supported only at the front and sides by the extensions 26 and the brace members 31, respectively.

In packaging the frame 16, required vertical space is minimized by removing the stabilizing rod 20, as in Fig. 2, and the hooks 17 are folded downwardly as shown by the dotted lines of Fig. 3.

In the modified frame 46 of Fig. 7, a central main track member 47 is used, of sufficient longitudinal strength to prevent bending when the rack 48 is weighted with garments and positioned at the front of the bag 15. The track member 47 is provided at its forward end with a vertical upward extension 50 welded to the middle of the front portion of the element 21. The rear end of the track 47 is welded to a vertical sleeve 51 provided with a thumbscrew 52 transversely threaded therein. The sleeve 51 is adapted to receive the stabilizing rod 20 whose vertical position is adjustably fixed by the thumbscrew 52. To provide increased rigidity of the frame, if desired, a short piece of wire 53 may be welded to the sleeve 51 and to the rear portion of the element 21. The sleeve 51 is so disposed that the rod 20 just clears the inside of the element 21.

A medial transverse tie member 54 is welded to the lateral sides of the element 21 and carries the two hangers or hooks 17 disposed generally as in the device of Fig. 2. Laterally outward of the hooks 17 and adjacent each of the lateral sides of the element 21, an auxiliary track member 55, paralleling the main track 47, has a front upward extension 56 welded to the front portion of the element 21 and is bent upwardly slightly to the rear of the median for a short distance and then forwardly and upwardly into conjunction with the tie member 54, and is welded thereto. Welded to the tie member 54, slightly inwardly of the respective hooks 17 and descending inwardly on either side into conjunction with the track 47 slightly rearwardly of the median,

are two tension elements 57 which transmit the load on the track 47 to the hooks 17.

The rack 48 is slidably engaged with the track 47 by means of a bearing 34, and the guide rod 58 welded thereto is similar to the guide rod 38 except that it is illustrated as provided with a rearward slide bearing 34 instead of the eye 49 of the frame of Fig. 2. The outer ends of the rack 48 are supported from the auxiliary tracks 55 by slide bearings 34' which may be smaller than but otherwise identical with the bearings 34 except for the omission of a guide rod welded to the side.

In place of the bearing 34' the ends of the rack 48 may slidably engage the auxiliary track 55 with a grooved roller or sheave 60, as illustrated in Fig. 8, with the rack 48 having an upward extension 48' bent inwardly at its end to form the shaft on which the roller 60 is rotatable. Also, in place of the bearing 34', the lateral sides of the element 27 may be replaced by a light generally L-shaped track 27', as illustrated in Fig. 9, and the rack 48 provided with an upward extension 48'' bent outwardly at its end to form a shaft rotatably engaging a roller 61 arranged to roll along the bottom of the L.

At the middle of the front portion of the element 27 there is welded an eye 62 to which may be attached a chain 63 (Fig. 6) whose other end is adjustably attached to a screw-hook 64 mounted on the front edge of the shelf 45. This constitutes an effective arrangement for preventing forward angle tilting of the bag and may be used alternatively in place of the stabilizing rod 20.

The operation of this modification is identical with that for the device of Fig. 2 except that a single guide rod is used to maintain the rack perpendicular to the tracks, and the vertical adjustment for the stabilizing rod 20 is integral with the sleeve 51. A handle 49 is provided for convenience in sliding the rack 48 rearwardly or forwardly.

In Fig. 10, I illustrate a simplified frame 66 having a strong central main track 67 extending the full depth of the bag. A secondary track 68 mounted below and parallel to the track 67 and spaced a short distance therefrom, extends from the front end to slightly rearwardly of the median. A vertical upward extension 70 of the forward end of the track 68 is welded to the middle of the front portion of the element 27 and a vertical upward extension 71 of the rearward end of the track 68 is welded to the track 67. The tie member 54, hooks 17, and tension elements 57 welded to the track 68 at the rearward end, are identical with the construction of the similarly numbered parts shown in Fig. 7. The forward end of the track 67 is welded to the extension 70 and the rearward end is welded to a vertical sleeve 72 which in turn is welded to the central point of the rearward portion of the element 27.

The transverse rack 74 of this modification is slidably engaged with both the tracks 67 and 68 by means of the slide bearing 75 which is similar to the bearing 34 except that the opening 76 and the shell 35' of the bearing 75 are considerably vertically elongated to include the track 68 in the opening 76. The bearing 75 supports the rack 74 to which it is attached in a manner similar to the attachment of the rack 33 to the bearing 34. The bearing 75 is supported on the track 67, the top of the shell 35' being spaced from the track 67 by the ball 36. The track 68 functions as a guide to keep the bearing 75 in vertical alignment and consequently the rack

74 in a horizontal plane at all times. A guide rod 77 is welded to the side of the bearing 75 and extends rearwardly for approximately half the depth of the bag to an eye 78 which slidably engages the rearward half of the track 67, keeping the rack 74 transversely aligned at all positions of its translatory movement. The ends of the rack 74 are turned upwardly for a short distance high enough to allow placement thereon of hangers such as the hanger 44. Wire tension elements 80 are welded respectively between each of the ends of the rack 74 and the top of the bearing 75 to prevent the rack 74 from sagging at the ends due to loading.

This modification functions similarly to the devices previously described. The sleeve 72 is adapted to receive the stabilizing rod 20 which could be locked in place by a thumbscrew 73 threaded transversely into the sleeve. An eye, similar to the eye 62 of the modification shown in Fig. 7, could be attached to the frame 66 for use with the chain 63, as an alternative for the stabilizing rod 20.

It is evident from the foregoing that the various means of slide engagements illustrated may be largely interchanged, and sleeve or roller bearings may be used in place of the sliding eye or the ball engagements shown.

Furthermore, it is to be understood that my invention is not limited to the use of only two hooks 17 as shown in the several modifications illustrated, or the two track members 25, but may use as many hooks and as many tracks supported substantially therefrom as necessity warrants, for example three or four hooks and tracks for very wide bags. Also the handle 49 may be applied to any of the racks, rather than only to the rack 48, as illustrated in Fig. 7.

Although the front opening 22 of the bag 15 is shown as rectangular and closed by a flap 23 hinged at the side, it is obvious that other type openings such as bottom-hinged or V-shaped openings may be used.

Although the invention has been described in considerable detail, such description is intended as illustrative rather than limiting, as other embodiments will be evident to those skilled in the art, as well as obvious modifications in construction and arrangement of parts, without departing from the spirit of my invention.

I claim:

1. In combination with a non-collapsible suspension frame for a rectangular garment bag adapted to be disposed generally horizontally within and extend from front to rear of the upper part of the bag and having a plurality of suspension hooks attached to said frame disposed in spaced relation along the transverse median portion thereof, a longitudinal track extending the full length of said frame dependent from and fixed to the forward end and to the median portion of said frame, a transverse garment hanger rack slidably engageable with said track for translatory movement between said forward end and said median portion, means for maintaining said rack in a horizontal plane, and guide means fixed to said rack and slidably engageable with said track between said median portion and the rearward end of said track for maintaining said rack at right angles to said track.

2. In combination with a non-collapsible suspension frame for a rectangular garment bag adapted to be suspended from a horizontal rod vertically spaced below an overlying horizontal shelf and to fit within and extend from front to

rear of the upper part of the bag and to maintain it in horizontally distended condition, a garment hanger rack slidably mounted on the frame below and parallel to said rod, means for guiding said rack for translatory movement in a horizontal plane between a rearward position vertically below said rod and a forward position at the front of said bag, means for preventing angular tilting of said rack out of horizontal position, means cooperatively associated with said shelf for preventing angular tilting of the plane of translatory movement of said rack about said rod as an axis, and means for maintaining said rack parallel to said rod.

3. In combination with a non-collapsible suspension frame for a rectangular garment bag adapted to be suspended by a plurality of hooks attached to said frame and disposed in spaced relation along the transverse median portion thereof from a horizontal rod vertically spaced below an overlying horizontal shelf and to fit within and extend from front to rear of the upper part of the bag and to maintain it in horizontally distended condition, means associated with said frame and engaging said shelf for preventing downward tilting of the forward end of said frame, a longitudinal track extending the full length of said frame dependent from and fixed to the forward end and to the median portion of said frame, a transverse garment hanger rack slidably mounted on said track for translatory movement between said forward end and said median portion, means for maintaining said rack in a horizontal plane, and guide means fixed to said rack and slidably engageable with said track between said median portion and the rearward end of said track for maintaining said rack at right angles to said track.

4. The invention set forth in claim 3 characterized in that said frame is provided with a flexible garment bag disposed thereon, said bag having a forward opening of substantially the full width of the bag front and extending vertically from just below the top of the bag to a substantial distance downwardly thereof, a closure flap for said opening, peripheral slide fastening means for securing and opening said flap, and the top of said bag having suitable holes for passage of said hooks and said first mentioned means.

5. The invention set forth in claim 1 characterized in that said hooks are pivotally attached to said frame so that they may be turned downwardly into the body of said frame.

6. The invention set forth in claim 1 characterized in that the slidable engagement of said rack with said frame is by a ball slide bearing.

7. The invention set forth in claim 3 characterized in that said first mentioned means comprises a vertically disposed stabilizing rod adjustably and lockably secured to said frame centrally of the rearward portion thereof and extensible upwardly for contact with the lower surface of said shelf.

8. The invention set forth in claim 1 charac-

terized in that said track is centrally disposed and constructed for transmission of vertical force to a hook on either side by an angularly disposed tension element having one end respectively connected to said frame adjacent said hook and the other end connected to said track adjacent said median portion.

9. In combination with a non-collapsible suspension frame for a rectangular garment bag adapted to fit within and extend from front to rear of the upper part of the bag and to maintain it in horizontally distended condition and having a plurality of suspension hooks attached to said frame and disposed in spaced relation along the transverse median portion thereof, a plurality of parallel longitudinal tracks dependent from said frame, a transverse garment hanger rack slidably mounted on said tracks for translatory movement between the forward end of

10 said frame and said median portion, and guide means for maintaining said rack at right angles to said tracks.

11. The invention set forth in claim 1 characterized in that said track is centrally disposed, 25 said frame is provided with an auxiliary track adjacent each side edge thereof paralleling said first-mentioned track and extending from said forward end to said median portion, said auxiliary tracks being suspended from and fixed to 30 said frame, and the outer ends of said track being supported by and in slidable engagement with said auxiliary tracks.

12. The invention set forth in claim 3 characterized in that said first-mentioned means comprises a chain having one end attached to said frame centrally of the forward portion thereof, and that said shelf is provided with means for detachably engaging one of the links of said chain.

13. The invention set forth in claim 11 characterized in that each end of each of said tracks is reinforced against downward bending by an angularly disposed tension element having one end respectively connected to said frame adjacent the respective associated hook and the other end connected to said track adjacent the end thereof.
